(57) **CLAIM**

The ornamental design of a specimen cup and transfer apparatus, as shown and described.

DESCRIPTION

FIG. 1 is a perspective view of a specimen cup and transfer apparatus according to our new design;
FIG. 2 is a front elevation view thereof;
FIG. 3 is a rear elevation view thereof;
FIG. 4 is a left end elevation view thereof;
FIG. 5 is a right end elevation view thereof;
FIG. 6 is a top plan view thereof; and,
FIG. 7 is a bottom plan view thereof.

The broken lines shown are included for the purpose of illustrating the unclaimed portions of the article and form no part of the claimed design.
